UNITED STATES PATENT OFFICE.

EDMOND B. BIGELOW, OF CHICAGO, ILLINOIS, ASSIGNOR TO HIMSELF, SOLOMON L. BIGNALL, AND CHARLES J. GLENN, ALL OF SAME PLACE.

LAMP.

SPECIFICATION forming part of Letters Patent No. 334,558, dated January 19, 1886.

Application filed April 29, 1884. Serial No. 129,782. (No model.)

To all whom it may concern:

Be it known that I, EDMOND B. BIGELOW, residing at Chicago, in the county of Cook and State of Illinois, and a citizen of the 5 United States, have invented certain new and useful Improvements in Lamps, of which the following is a full description, reference being had to the accompanying drawings, in which—

10 Figure 1 is a vertical section of a hand-lamp; Fig. 2, an elevation of the central tube with the wick-holder in place; Fig. 3, a cross-section on line 1 1 of Fig. 2; Fig. 4, an elevation of the cone; Fig. 5, an elevation of the 15 collar of the fountain by which the cone is attached; Fig. 6, an elevation of the fountain of a bracket-lamp, partly broken away at the bottom; Fig. 7, an elevation of the upper end of the central tube.

20 The object of this invention is to improve the construction and operation of center-vent or Argand lamps, so as to adapt them more perfectly to the use of kerosene or other carbon oils; and its nature consists in the several 25 combinations and improvements hereinafter set forth and claimed as new.

In the drawings, A indicates the fountain or vase; B, the base; C, the burner; D, the neck or collar of the burner; E, the fountain-collar; 30 a, the central tube; b, the supporting-tube for the fountain; c, the groove for supporting the lower bridge of the button-stem; d d', bridges or spiders for supporting a button-stem; e, button-stem; f, button; g, the screw collar and 35 thread by which the position of the button may be adjusted; h, wick-holder; i, notches or teeth for moving the wick-holder; j, hooks or projections for insuring the movement of the wick with the holder; k, grooves in the wick- 40 holder for permitting it to pass the shaft of the wick-ratchet; l, wick-ratchet shaft; m, button for operating the wick-ratchet; n, the ratchet; o, box located within the central tube for inclosing the wick-ratchet; p, side tube of 45 the box o, for the wick-ratchet shaft; q, swelling or projection in the box o, for the inner end of the ratchet-shaft; r, vertical and horizontal slot in the collar D of the burner; s, a similar slot in the collar E of the fountain; t, 50 collar for attaching the lamp to a bracket or other support; u, hole in collar t, for connect-

ing it with the lower end of the button-stem; v, vent-holes in base; w, wick-space; x, space for the exterior current of air; y, perforated sheet of metal or wire-gauze screen; z, upper 55 contracted end of cone.

The lamp shown is usually made of brass or other sheet metal that can be spun, stamped, or pressed into the desired shapes of the form shown, or of other suitable forms which are not 60 a substantial departure therefrom.

The center tube, a, is made of a length sufficient to pass from the upper end of the interior part of the burner down to the top of the base. Within this tube is located a box or 65 casing, o, which surrounds the wick-ratchet and prevents oil from passing to the interior of the tube in use. This box, as shown in Fig. 3, is provided with a side tube, p, which surrounds the shaft l, and prevents the leak- 70 age of oil at this point. The swell q, for the inner end of the shaft l, may be omitted, if desired, as the device works well in use without it. Its use, however, gives the wick- 75 ratchet a little steadier position.

The wick-holder is made in the form shown in Fig. 2, and is provided with notches or cross-bars to engage with the teeth of the ratchet u, by means of which the wick-holder is raised or lowered. The wick-holder is provided with small upwardly-inclined teeth j, as shown, which teeth engage with the wick and insure its uniform raising, but being made upwardly inclined, as shown, and of thin metal, so as to yield laterally. This holder can 80 be run down, so as to make a new engagement with the wick after it has reached its upper limit in use, and by holding the wick against the tube a this wick-holder can be run down by the ratchet, and a new engagement is thus 85 made with the wick without taking it out of the lamp and without removing more than the cone of the burner, thus doing away with the necessity of taking the lamp apart to readjust the wick, and as the wicks are originally 90 inserted with their surplus material below the holder, this arrangement does not interfere with putting a new wick into the lamp. This arrangement also enables me to use a short 95 wick-holder, which gives the wick greater 100 freedom within the body of the fountain.

The construction of the wick-raising ratchet

does not differ from ordinary constructions, except that the hole through the ratchet-wheel is square, and the corresponding part of the shaft *l* is also square in cross-section. By this 5 construction the ratchet-wheel can be placed in the box *o*, and the shaft *l* slipped into it, and the rotation of the ratchet is thus secured, even though the soldering or pressing should be defective or become loosened by use, and 10 thus become inoperative, which frequently happens when the shaft is round for its entire length.

In the center of the central tube I locate 15 the button-stem *e*, which is made of as small a size of wire as will answer the purpose, and support it by the bridge *d* at the bottom, and I hold the upper end in position by the bridge or spider *d'*, which bridge may be secured either to the center tube or to the stem, as may 20 be most convenient.

In constructing lamps for the burning of carbon oil it is essential to make provision for the introduction of as large a body of air as is possible. For this reason I use as large a tube 25 as can be properly made for the size of the burner to be applied, and I make the stem *e* of as small a wire as will be sufficient to properly sustain the button, while the bridges or spiders are made as open as possible to give them sufficient strength to support the stem, thus giving 30 the central tube as great a capacity as can be had with the fewest obstructions possible.

As shown in Fig. 1, the button *f* is made adjustable by the screw *g*, so that a nice adjustment of the air-currents can be had, when desired. For cheap lamps and for lamps to be used by unskilled persons it will, however, be preferable to make the adjustment at the factory, and for this purpose the screw-thread 40 may be omitted and the button be simply slipped on over the upper end of the stem *e*. The concave form of the button *f* is the most desirable form for use, as this construction prevents any eddying of the air-currents in 45 contact with or in proximity to the flame. This button, as will be seen from Fig. 1, is nearly but not quite as large in diameter as the diameter of the cone *z* at its upper end. The cone is curved inward, as shown, so that as 50 the combustible vapor ascends from the wick the exterior current of air is sharply impinged against it, and by reason of the large diameter of the button the interior current is also strongly impinged against the ascending current of vapor and flame, and by reason of this 55 arrangement and adjustment of diameters between the cone and button and the narrow space between them a thorough intermixture of air is made with the vapor, and, the rapidly-ascending currents of air being thus made to practically cross each other, they have the effect of a blast, in addition to supplying and directing the proper amount of air to the vapor, and I thus produce a perfection of combustion, which I believe has not heretofore 60 been attained in lamps for burning carbon oil.

For the purpose of readily separating the cone from the burner for cleaning purposes and the easy insertion of wicks, I provide the slipping collar *D* of the cone with the slot *r*, 70 which is of the form commonly known as "bayonet-catch," the locking-pin, however, in this case being the shaft *l* of the wick-raiser. I also provide the collar *E* of the fountain with a similar slot, *s*; but in this construction it 75 will be necessary for either this collar or the central tube to be adapted to partly rotate.

In this construction the ratchet-shaft is inserted in the vertical portion of the slot *s*, then it or the collar is turned to bring the shaft into the horizontal portion of the slot, the cone is then inserted, the horizontal portion of the slot *r* passing the shaft *l*, the collar *D* of the cone is then turned, so as to bring up the horizontal portion of this slot across the shaft *l*, and 85 thus close the opening for the shaft *l* with a closer fitting than a round hole. By this arrangement parts of the burner are easily separated for the purpose before mentioned. For cheaper lamps the central tube may be placed 90 in position and rotated to the end of the slot *s* before it is soldered to the bottom of the fountain or other parts of the lamp.

The base *B* of the hand-lamp is provided with vent-openings *v*, which prevent the shutting off of the air by setting the lamp down, so that the central tube is at all times provided 95 with a free and full current of air.

For the attachment of lamps to brackets, gas-fixtures, or other fixed support, I provide 100 the collar *t*, shown in Fig. 6, with an interior screw-thread of the regulation size to fit these fixtures, and with a hole, *u*, to fit the lower end of the stem *e*. By means of this collar the lamp can be readily attached to any 105 supporting-fixture and be readily put in position or lifted off by slipping the stem *e* into or out of the hole *u*.

It will of course be understood that I do not lay any claim to the invention of an 110 Argand or center-vent burner, my improvements in this respect being only such as are hereinafter claimed; and I do not claim, broadly, the application of teeth to a wick-holder. My improvement in this respect consists in 115 placing the teeth at an upwardly-inclined angle, as described, so that the holder can be lowered, when desired, without taking the wick with it.

I do not claim the combination of a wick- 120 raising shaft with a slotted burner-tube, as such of itself is not my invention.

What I claim as new, and desire to secure by Letters Patent, is—

1. The tube *b*, having groove *c*, in combination with the bridges or spiders *d* *d'*, stem *e*, and button *f*, substantially as described. 125

2. The combination of tube *a*, tube *p*, and the ratchet-wheel covering-box *o*, located within tube *a*, substantially as described.

3. The oil-tight ratchet-wheel box *o*, located 130 within the tube *a*, and tube *p*, in combination

with the wheel *n*, and shaft *l*, substantially as described.

4. The combination, with a tube, *a*, of a wick-holder, *h*, having upwardly-inclined and laterally-yielding spring-teeth *j*, for the purpose of effecting a new engagement of the teeth with the wick when the latter is held and the wick-holder is lowered, substantially as described.
- 10 5. The combination, with a tube, *a*, of the wick-holder *h*, applied to slide directly on the tube, and having the upwardly and outwardly

inclined and inwardly yielding spring-teeth *j*, for effecting a new engagement with the wick when the latter is held and the wick-holder 15 lowered, substantially as described.

6. The screw-threaded collar *t*, in combination with the stem *e* and bridge *d*, substantially as and for the purpose set forth.

EDMOND B. BIGELOW.
